LOREN J. WICKS, OF BRIDGETON, NEW JERSEY, ASSIGNOR TO HIMSELF, WILLIAM SELSER, CHARLES N. SELSER, JOHN A. SELSER, GEORGE W. TURNER, AND JOHN H. POOLE.

Design No. 3,836, dated February 1, 1870.

DESIGN FOR BOTTLES.

The Schedule referred to in these Letters Patent and making part of the same.

I, LOREN J. WICKS, of Bridgeton, county of Cumberland, State of New Jersey, have invented a Design for the Body and part of the Neck of a Bottle, of which the following is a specification.

The figure, in the accompanying drawing, represents my design, which consists of the body A and part B of the neck of a bottle, the body having rounded sides, and gradually increasing in diameter from the base *a* to the dotted line *x*, from which point the body is rounded abruptly, and decreases in diameter to the collar *f*, where the body of the bottle meets the neck, the latter having slightly tapering sides, which

meet the edge of the collar with abrupt curves, as shown in the drawing.

I claim the design for the body and part of the neck of a bottle, substantially as represented in and by the accompanying drawing.

In testimony whereof, I have signed my name to this specification, in the presence of two subscribing witnesses.

LOREN J. WICKS.
